UNITED STATES PATENT OFFICE.

WILLIAM R. BROCK, OF SHELTON, CONNECTICUT, ASSIGNOR TO M & P CORSET COMPANY, OF DERBY, CONNECTICUT.

CORSET.

Application filed January 29, 1924. Serial No. 689,300.

This invention relates to corsets and more particularly to a type of corset in which are employed devices for adjusting the garment to the body of the wearer so that a comfortable fit will be had and at the same time the desired appearance of the figure will be produced. It is also contemplated that proper support and confinement shall be given to various parts of the body where such is needed.

One object of my invention is to provide a new and improved form of corset which shall give the desired form to the figure of the wearer and at the same time will be comfortable and easily adjusted to the body.

Another object of my invention is to provide an improved type of corset which may be readily adjusted to fit the body of the wearer and at the same time may be quickly fastened or clasped in place when worn.

A still further object of the invention is the provision of a corset provided with elastic sections or gores, and having means for adjusting the tension placed upon these elastic sections so that the proper or desired appearance of the figure will be produced, and at the same time, the corset may be worn with comfort and ease.

To these and other ends the invention consists in the novel features and combination of parts to be hereinafter described and claimed.

In the accompanying drawings:

Fig. 1 is a perspective view illustrating a corset constructed in accordance with my invention;

Fig. 2 is a sectional view on line 2—2 of Fig. 1;

Fig. 3 is an enlarged sectional view through the front portion of the corset;

Fig. 4 is an elevational view on an enlarged scale showing the front outer portion of the garment; and

Fig. 5 is a view similar to Fig. 4 showing the inner portion of the garment, or the reverse side of the part shown in Fig. 4;

Fig. 6 is a fragmentary front elevational view of a modified form of my invention.

In carrying out the present invention, the garment, which may be of the closed back type, as shown, or which may, if desired, be divided into sections and provided with back laces, may be made with elastic sections at

its front portion adjacent the front steels. 55 These elastic sections are, of course, yielding and extend from the upper to the lower portion of the body of the garment, to permit the corset to adjust itself to the body of the wearer, and while confining the parts of 60 the body to the desired extent will yield sufficiently to prevent any discomfort to the wearer. In order to adjust to some extent the tension to which the elastic sections may be subjected, devices are provided for 65 taking up the tension on these sections so that after the garment is once fitted to the wearer it is only necessary to secure it in place by the clasps or hooks attached to the front steels or busks, and by this arrangement tedious lacing each time the garment is worn is obviated.

In addition, in order to give additional strengthening and supporting features to the garment, elastic or yielding strips are connected, adjacent the elastic sections, to the body of the garment at the inner side thereof, which improve the wearing qualities of the garment, as well as the comfort with which it is worn.

While in the garment shown, the elastic sections as well as the adjusting devices therefor are arranged at the front of the garment adjacent the busks it will be obvious that such sections may be placed at the sides 85 or at the rear of the garment if desired, without departing from the principles of the invention in some of its aspects.

In the drawings I have illustrated a corset comprising a body portion 10 of the closed back type, and the front steel section or busks 11 and 12 provided with suitable clasps or the like 13, by which the steels may be connected together upon the body of the wearer. Adjacent each front busk and between these busks and the one-piece fabric body portion of the garment, are provided the yielding or elastic sections 14 and 15. These sections, as shown in Figs. 4 and 5, may preferably be made of a number of short strips of elastic fabric 16 extending circumferentially of the garment, the edges of these elastic strips being sewed or otherwise secured together so that a substantially solid elastic or yielding section results. This section extends substantially from the upper to the lower edge of the garment and as the front steel sections are somewhat shorter

than the body portions of the garment at the sides thereof, the lowermost elastic strips 17 may be inclined upwardly toward the front steels and overlap to some extent the adjacent strips 16. The inclined or diagonal strips 17 just referred to, insure the application of proper tension to the lower edge of the garment at the sides thereof so that a smooth and close fit will be produced.

10 Adjacent each of the front elastic sections an inelastic flap or adjusting member 19 is secured to the body portion 10 of the corset, and a co-operating member 20 is secured to the adjacent edge of the front busk. 15 These two adjusting members 19 and 20 are provided with openings 21 and are designed to be drawn together by means of laces 22, so as to adjust the tension to which the elastic section is subjected. As shown, this adjusting section is somewhat shorter than the body of the garment and does not extend to either the upper or lower edges thereof, although changes in this respect may be made if desired.

20 25 Preferably, however, the member 20 is extended at its lower end to provide a downwardly extending strap 23 to which one end of a hose supporter 24 may be connected, the other end of which is connected to the corset adjacent the lower edge of the front steel section or busk as at 25. The support clasp 26 may be loosely threaded upon the supporter 24 so that the tension may always be 30 equally distributed between the two portions 35 of the supporter. This arrangement assists in maintaining the front of the corset in the proper position and at the same time avoids the obvious impracticability of connecting either end of the hose supporter to 40 the elastic section.

45 At the inner side of the garment at each side of the front thereof is provided a yielding tension strap 27 preferably made of strong elastic material. As shown in Fig 5, this strap is inclined rearwardly and spans the adjacent elastic section. One end of each of these straps is connected to the front steel section, and the other end connected to the body of the garment at the side thereof as the strap is preferably somewhat longer than the width of the elastic section. This strap serves to give the proper support and confinement to the parts of the body to which it is adjacent and at the same time 50 reinforces the elastic section and assists it in performing its functions. As the rear end of the strap is connected to the corset body rearwardly of the adjusting flap 19 the tension of this strap is also adjusted 55 to some extent by the laces 22.

60 It will, of course, be understood that additional hose supporters may be secured to the lower edge of the body of the garment as desired by the wearer, and in some instances, the body of the corset may be di-

vided into two parts which may be laced together in the customary way.

When the garment is fitted the laces 22 are loosened and the corset is put on. The laces are then adjusted until the garment 70 properly fits the figure of the wearer, the fabric and non-elastic flaps 19 and 20 serving to confine the portions of the body adjacent thereto and also to adjust the tension upon the elastic sections 14 and 15, as well 75 as upon the straps 27. After the garment has once been fitted as described, no change or manipulation of the laces 22 is necessary and the garment may be conveniently fastened by means of the clasps secured to the 80 front steel sections.

In Fig. 6 of the drawings I have shown a somewhat modified construction wherein the depending strap 23^a instead of hanging loosely from the member 20, as shown in Fig. 85 1, is stitched to the front busk 11 along the adjacent edges of these two members, as shown at 30. In this manner the member 23^a is securely held in place, and any tendency of this member to become wrinkled is 90 obviated, and it is caused to lie flatly or smoothly along the front of the garment.

95 While I have shown and described a preferred embodiment of my invention, it will be understood that it is not to be limited to all the details shown but is capable of modification and variation within the spirit of the invention and within the scope of the appended claims.

100 What I claim is:—

1. A corset comprising front steel sections, an elastic section connected to each of said front steel sections, a fabric body portion extending about the body of the wearer and connected to the opposite edges of said elastic sections, an inner strap at each side of the front steel sections and connected at one end to said section, said straps being inclined rearwardly and upwardly and connected at their other ends to the fabric body portion of the corset at the sides thereof, said straps lying beneath the elastic sections and between the upper and lower ends thereof, and adjusting flaps connected to the front steel sections and to the adjacent edges of the body portion of the garment and adapted to adjust the tension on the elastic sections and on said inner straps. 115

2. A corset comprising front steel sections, an elastic section connected to each of said front steel sections, a fabric body portion extending about the body of the wearer and connected to the opposite edges of said elastic sections, an inner elastic strap at each side of the front steel sections and connected at one end to said section, said straps being inclined rearwardly and upwardly and connected at their other ends to the fabric body portion of the corset and lying below the elastic sections and between the upper and 130

- lower edges thereof, and adjusting flaps secured exteriorly to the body of the corset and designed to adjust the tension on said elastic sections and said elastic strap, one of 5 the adjusting members being extended downwardly to provide a depending strap and a hose supporter connected at one end to said depending strap and at the other end to one of the front steel sections.
- 10 3. A corset comprising a body portion and front steel sections, an elastic section adjacent each of the front steel sections and extending from the upper to the lower edges 15 of the garment, said elastic section comprising a plurality of strips arranged substantially horizontally of the body of the wearer, the sides of the body portion of the garment being longer than the front steel section, and an inclined elastic strip connecting the lower 20 ends of the front steel sections with the side portions of the garment below said elastic section.
4. A corset comprising a body portion and front steel sections, an elastic section adjacent each of the front steel sections and extending from the upper to the lower edges 25 of the garment, said elastic section comprising a plurality of strips arranged substantially horizontally of the body of the wearer, the sides of the body portion of the 30 garment being longer than the front steel section, and an inclined elastic strip connecting the lower ends of the front steel sections with the lower 35 portions of the garment and forming the lower portion of said elastic section.

In witness whereof, I have hereunto set my hand this 23rd day of January, 1924.

WILLIAM R. BROCK.
